Primary Examiner—Stella Reid*Attorney, Agent, or Firm*—Oblon, Spivak, McClelland, Maier & Neustadt**[57] CLAIM**

The ornamental design for a combined housing and fire extinguisher for an alcohol lamp, as shown and described.

DESCRIPTION

FIG. 1 is a front elevational view of a combined housing and fire extinguisher for an alcohol lamp showing my new design;

FIG. 2 is a right side elevational view thereof, the left side view being a mirror image of the right side;

FIG. 3 is a top plan view thereof;

FIG. 4 is a bottom plan view thereof;

FIG. 5 is a rear elevational view thereof; and,

FIG. 6 is a cross-sectional view thereof, taken along line 6—6 of FIG. 1.

FIG. 1

6

FIG. 2

FIG. 3

FIG. 4

FIG. 5
